UNITED STATES PATENT OFFICE.

SIMEON DESMOND PURDY, OF FAIRVILLE, NEW BRUNSWICK, CANADA, ASSIGNEE OF
ONE-HALF TO T. S. SIMMS & COMPANY, LIMITED, OF FAIRVILLE, NEW BRUNSWICK, CANADA, A CORPORATION OF CANADA.

BRUSH.

1,385,272.

Specification of Letters Patent. Patented July 19, 1921.

Application filed January 7, 1921. Serial No. 435,717.

To all whom it may concern:

Be it known that I, SIMEON DESMOND PURDY, a citizen of the United States of America, residing at Fairville, St. John county, New Brunswick, Canada, have invented certain new and useful Improvements in Brushes, of which the following is a specification.

My invention relates to brushes, and particularly to shaving brushes, the object of my invention being to provide a shaving brush of the tourist or traveler type having an improved general construction, and particularly an improved housing connection between the brush ferrule proper and the handle or casing of the brush.

In the accompanying drawings—

Figure 1 is a longitudinal section through a brush in which my invention is embodied in one form;

Fig. 2 is a section on the line 2—2, Fig. 1;

Fig. 3 is a partial longitudinal section showing the brush ferrule housed within the casing; and

Fig. 4 is a section on the line 4—4, Fig. 3.

In the present construction the brush comprises a tubular casing 5 of metal, celluloid, hard rubber or the like, within which is accommodated the ferrule 6 carrying the 30 knot 7 of bristles forming the brush proper. The stub end of the bristle knot 7 may be cemented directly to the ferrule 6, or to an independent ring 8 secured in any suitable fashion in the outer end of the ferrule 6. 35 As indicated, the ferrule is of a slightly frusto-conical shape at the brush end. The end 9 of the casing is likewise drawn to frusto-conical shape to limit the extent to which the ferrule may be pushed outward 40 at this end of the casing.

In order to maintain the ferrule in its extended position, indicated in Fig. 1, so that the brush 7 may be put to use, I provide a pair of studs 10 projecting through 45 holes in opposite sides of the ferrule, and normally pressed outward by an interposed coil spring 11, which bears against flanges 12 on the studs. A disk 13 closes the inner end of the ferrule and may be secured in 50 position in any suitable way. To receive the outwardly projecting ends of the studs, the inner face of the casing is provided with a pair of arcuate recesses 14 arranged diametrically opposite each other, and of a

depth and width sufficient to receive the 55 studs 10. To free the studs from these recesses 14, it is obviously only necessary to rotate the ferrule to a slight extent, thereby causing the studs to run up the inclined bottoms of the recesses to the interior surface 60 of the casing 5. The ferrule may then be pushed inward in the casing, the studs bearing against the inner surface thereof, and serving by their frictional engagement 65 therewith to maintain the brush housed within the casing, as indicated in Fig. 3. The end 9 of the casing is intentionally left open to insure ventilation of the bristles and thus prevent rotting of the latter, should 70 they be housed within the casing while wet.

The opposite end of the casing is tapped to receive a stop ring 15 screwed therein and having a central opening 16 to permit the insertion of a finger to advance the ferrule to the position shown in Fig. 1. If it 75 is desired to remove the bristle bunch for cleaning, the stop ring 15 may be unscrewed and the ferrule 6 withdrawn at this end of the casing.

The construction as a whole is extremely 80 simple, while at the same time the casing effectively retains and houses the brush when out of use. Its ready extrusion from the casing by the finger eliminates the necessity for operating slides, pushers, etc., which 85 commonly get out of order or become choked with soap.

Various modifications in detail and form of construction will readily occur to those dealing with the problem. Variations 90 within the purview of those skilled in the art, will be understood to fall within the scope of what I claim as my invention.

I claim—

1. In a brush of the type described, a tubular casing having an arcuate notch formed in the inner face of its wall, a brush-carrying ferrule slidable within said casing, and a latching element carried by the ferrule and spring pressed outward to engage said notch 100 and thus to hold the ferrule in brush-exposing position.

2. In a brush of the type described, a tubular casing, a brush-carrying ferrule slidable within said casing, and co-operating 105 readily freed latching elements for the ferrule and casing, said elements being completely housed within the casing and serving

to hold the ferrule against longitudinal displacement at one end of the casing, said latching elements being disengageable by relative rotary displacement of the parts.

5 3. A brush of the type described, comprising a tubular casing open at both ends having an interior recess adjacent one end, in combination with a brush-carrying ferrule longitudinally slidable within said casing, 10 and spring means carried by the ferrule and detachably engaging said recess to maintain the brush in extended position, said means engaging the interior of the casing in unlatched position and serving to frictionally maintain the brush housed within the casing.

15 4. In a brush of the type described, a tubular casing, a brush-carrying ferrule sliding within said casing, spring means carried by the ferrule and frictionally engaging the 20 interior of the casing to maintain the brush housed therein, means limiting the outward displacement of the ferrule at one end of the casing, and means at said end of the casing coöperating with the spring means 25 of the ferrule to hold the latter in brush-exposing position, said latching means being readily freed by relative rotation of the ferrule and casing to permit the ferrule to be longitudinally displaced within the casing 30 to brush-housing position.

35 5. In a brush of the type described, a tubular casing, a brush-carrying ferrule rotarily and longitudinally displaceable in the casing, friction means holding the ferrule 40 against longitudinal displacement in brush-housing position within the casing regardless of its relative rotary position therein, and latching on the elements at one end of the casing operative only in predetermined 45 relative rotary position of the ferrule and casing to hold the ferrule against longitudinal displacement in brush exposing position.

50 6. In a brush of the type described, a tubular casing open at both ends, a brush-carrying ferrule slidable within the casing, means at both ends of the casing to prevent the escape of the ferrule and concealed spring means readily freed by relative rotation of the casing and ferrule for holding 55 the brush against longitudinal displacement in brush-exposing position at one end of the casing.

60 7. In a brush of the type described, a tubular casing constricted at one end, a stop ring secured to the other end of the casing, said casing having a pair of arcuate notches on opposite sides of its inner surface adjacent one end of the casing, in combination with a frusto-conical ferrule longitudinally 65 slidable in said casing, and spring studs carried by said ferrule and engaging in said arcuate notches to maintain the ferrule in brush-exposing position at the constricted end of the casing.

65 In testimony whereof I have signed my name to this specification.

SIMEON DESMOND PURDY.
